UNITED STATES PATENT OFFICE.

WESLEY COLE, OF MENOMONEE, WISCONSIN, ASSIGNOR TO JOHN GRAY, OF SAME PLACE.

SAND-BAND.

SPECIFICATION forming part of Letters Patent No. 274,885, dated March 27, 1883.

Application filed January 4, 1883. (No model.)

To all whom it may concern:

Be it known that I, WESLEY COLE, a citizen of the United States, residing at Menomonee, in the county of Dunn and State of Wisconsin, have invented certain new and useful Improvements in Sand-Bands for Vehicle-Wheels; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of this invention in a longitudinal section. Fig. 2 is a perspective view. Fig. 3 is a perspective detail, showing the sand-band before it is attached to the hub.

This invention has relation to sand bands or shields for the hubs of vehicle-wheels; and the novelty consists in a band or shield having flaring ends and a circumferential depression between said ends, in combination with an axle having an annular beading or collar formed thereon, and engaging one of the ends of the band as will be hereinafter more fully described.

In the annexed drawings, the letter A designates the hub of a wheel; and B represents the sand-band or dust-guard, which is secured by one of its flaring ends, e, around the inner

end of the hub of the wheel. The other flaring end, g, extends over and around the annular beading or raised collar d on the axle, and surrounds the same sufficiently closely to prevent the access of sand or mud to the spindle within the hub. Between the flaring ends e and g the band is concave or depressed circumferentially, in order to deflect sand and dust from its ends toward its depressed central portion, z. The object of the flaring end g is to provide for a close engagement of the band B with the beading or collar d, and on account of the peculiar concave shape of the band it serves to deflect from the inner end of the hub the particles of sand and mud which are thrown against the band when the wheel is in motion.

Having described this invention, what I claim, and desire to secure by Letters Patent, is—

The sand-band B, having the flaring ends e and g, and the circumferential depression z between said flaring ends, in combination with the axle having the annular bead or collar d within the inner flaring end of the band, and engaging the same, substantially as specified.

In testimony whereof I affix my signature in presence of two witnesses.

WESLEY COLE.
